CUTLERY HOLDER

Donald E. Everburg, Southbridge, Mass., assignor to
American Optical Corporation, Southbridge, Mass., a
corporation of Delaware

Filed Sept. 25, 1968, Ser. No. 13,706

Term of patent 7 years

Int Cl. D7—99
U.S. Cl. D44—29

FIG. 1 is a perspective view of a cutlery holder showing my new design;

FIG. 2 is a perspective view of the same cutlery holder taken from the opposite corner;

FIG. 3 is a top plan view of the same; and

FIG. 4 is an elevational view from the right of FIG. 3. The knife shown in broken lines in FIGS. 3 and 4 is for illustrative purposes only. The rear of the cutlery holder is substantially plain and unornamented and is not shown in the drawing for that reason.

I claim:

The ornamental design for a cutlery holder, substantially as shown and described.
